Application August 27, 1948, Serial No. 46,379

5 Claims. (Cl. 45—57)

1

This invention is concerned with improvements in book-holders with special reference to a clip form of book-holder that may serve as a book-end and/or book-rest; the present invention constituting an improvement on the invention disclosed in a prior patent, Number 1,942,456 granted me on January 9, 1934, for Bookholder.

The invention is concerned particularly with improvements in the features of construction of this type of book-holder by means of which it may be manufactured by simple inexpensive production methods in large quantities and with its novel means for operatively distorting certain engaging portions thereof to facilitate engagement with the cover-boards of a book or other suitable objects.

A further object of the invention is the provision of a one piece form of this type of book-holder that will not require any assembly in its construction.

A still further and important object of the invention is to provide a simple and inexpensive means for operating its engaging portions.

Another object of the invention is to provide a one piece reading-rest in a clip form of a book-end so that it may always be handy for immediate use and easily disposed of after use as a reading-rest, as a book-end between and at the ends of books on library shelves or as book-ends on desks and tables.

And still another object of the invention is the provision of a one piece book-end that is engageable with a similar book-end to form an easel stand having a projecting shelf for supporting books and reading matter in an inclined position thereon.

These and other objects are successfully secured by means of the construction herein disclosed, as will be apparent from the following description.

Referring to the drawing:

Figure 1 is a perspective view of one form of this invention in a position that may serve as a book-end;

Figure 2 is a perspective view of the invention showing the engaging portions operatively distorted for engagement;

Figure 3 is a perspective view of a pair of the book-ends shown in Figure 1 serving to prop up a book in open position;

Figure 4 is a perspective view showing method of distorting engaging portions; and

Figure 5 is a perspective view showing method of engaging one of a pair of the book-ends with the other to form an easel stand.

The particular embodiment shown in the draw-

ing for the purpose of illustrating the preferred form of this invention, is preferably made from a length of flat-wire metal and formed into a plurality of bends with both ends thereof remaining free, but other forms of this invention may be constructed from various shaped rods of suitable material although a flat-sided material is preferred and may be of metal or a suitable plastic and formed by bending, molding or die blanking and forming.

The device comprises two side-by-side base panels and two side-by-side support panels, the latter being positioned in a plane transverse to the plane of the former. In its preferred form, the entire device is made from a single strip of elastic material, either of metal or of stiff plastic. The term "elastic" is used in its technical sense, as referring to springiness, i. e., the tendency to recover quickly after distortion.

10 In Figure 1, it will be seen that the panels forming the base member are formed of two loops of this strip, the adjacent or inner legs A and B of each loop being substantially parallel to the outer legs C and D, which are spaced from A and B laterally, in the plane of the base. These outer legs are connected, across one end of the base member, by a bridge portion G; and each outer leg, at the opposite end of the base member, is connected by a bridge portion E or F to the appropriate inner leg, A or B respectively.

15 The inner legs A and B are bent, transversely of the plane of the base, along a line O—N which is parallel to the bridge portion G. They thus rise from the plane of the base in side-by-side relationship, forming the inner legs H, I of the loops which constitute the prop member. They are reversely bent outwardly, as at L and M, and their extremities J and K extend towards the plane of the base member but preferably terminate

20 short of that plane.

The upright or prop members H—I are normally parallel with each other, but may be moved laterally to an inclined position therefrom when it is desired to distort the base for engagement purposes.

25 In constructing the invention the flat sides of the flat-wire are bent to lie flatwise with the plane in which its various members are formed.

In using the device of the present invention, 30 the loops of the prop member are grasped with one hand, scissor-fashion, as shown in Figure 4, and are spread outwardly from each other by opening the hand. This involves distortion of the entire structure, part of the twist being taken up in the bridge or connecting member G, part

in the links E and F, and part of it in the twisting of the inner and outer legs of the respective loops. Obviously, the central elements H, I of the prop member will no longer be adjacent or substantially parallel, but the inner legs A, B of the base will maintain substantially parallel relationship during this operation. With the outer loops spread apart, as just described, it becomes a simple matter to apply the base member to the upper edge of the binding board of a standard book cover. When this is done, as is clearly seen in Figure 3, the outer legs of the base member C, D and also the bridging connection G will lie on one side of the cover board, whereas the inner adjacent legs A, B will lie on the opposite side. The torsional stress imposed by distortion of the device will cause the cover board to be firmly held between the outer legs and the inner legs of the base member.

The ease with which the device may be applied to book cover boards, as just described, constitutes a substantial advantage; since there is no necessity for rubbing or sliding contact, which might otherwise scar or damage the surface of the binding. This feature of pre-opening the engaging members for engagement is very useful for engaging many other suitable objects including the book-ends as illustrated in the drawing; the similar members being all spaced alike to facilitate the engagement of one book-end with the other to form an easel stand as shown in Figure 5, the upright members H—I and the handle members J—K of one book-end being engaged between the central engaging members A—B, the adjacent side engaging members C—D and the end engaging member G. This easel stand can also be used in an upside-down position from its illustrated position shown in Figure 5 of the drawing.

It is obvious to persons skilled in the art that numerous variations of the means for operating the engaging members may doubtless be devised and that other forms of the novel flat-sided engaging members may be made without departing from the principles of my invention. I, therefore, do not wish to be limited to the precise details of construction set forth, but desire to avail myself of such variations and modifications as come within the scope of the appended claims.

What is claimed is:

1. A book-holder comprising an integral piece of flat-wire bent edgewise near the middle in substantially one plane to form a major loop having substantially parallel sides, said flat-wire having both its ends further bent edgewise inwardly in the same plane to form two inward loops that are integral and parallel with the sides of said major loop; said ends being further bent at an angle out of the plane of the major loop to provide a pair of side-by-side supports, each incorporating a loop in the plane of said supports and lying generally in a plane transverse to the plane of said major loop.

2. A book-holder comprising an integral piece of flat-wire bent edgewise near the middle in substantially one plane to form a major loop having substantially parallel sides, said flat-wire having both its ends further bent edgewise inwardly in the same plane to form two inward loops that are integral and parallel with the sides of said major loop; said ends being further bent at an angle transversely of the plane of the major loop and lying generally in a plane transverse to the plane of said major loop.

3. A book-holder comprising a piece of flat-wire describing a loop at each of its ends to form dual prop members constituting a support-side and further forming a base consisting of two loops at an angle transverse to said support-side and a connecting member integral with said loops, all the elements of said base normally lying in one plane, but at least the connecting member being of elastic material and being distortable out of said plane by movement of said prop members.

4. A book holder comprising a support side having a pair of movable planar elements with their inner edges normally together; a base member extending transversely to the plane of said elements, having side and central portions normally lying in the same plane; distortable connections between said side and central portions; and connections between said planar elements and said central portions constraining the said portions to move out of their normal plane upon separating movement of said planar elements, to provide an opening between said side portions and said central portions to receive and resiliently secure the cover of a book.

5. A book holder comprising a planar base member and a support positioned in a plane transverse the plane of the base member, said base member comprising two adjacent loops of elastic material, each having substantially parallel inner and outer legs; joined at one end by an elastic link bridging the outer legs and at the other end by a pair of elastic links each connecting one outer leg with an inner leg; the adjacent inner legs rising transversely of the plane of the base member to form adjacent and substantially parallel central elements of the support member, said central elements being reversely bent outwardly, to form a pair of lateral wing members; the reversely bent outer extremities being also in the plane of the support and terminating adjacent the plane of the base member.
